CUTTER BAR AND CUTTER CHAIN

John S. Beltz, Columbus, Ohio, assignor to The Jeffrey Manufacturing Company, a corporation of Ohio.

Application June 7, 1934, Serial No. 729,529

9 Claims. (Cl. 262—33)

The present invention relates to a cutter bar and cutter chain construction for mining machines.

An object of the invention is to provide a cutter bar and cutter chain of such construction as to minimize wear and in which the parts which are subject to wear may be readily replaced.

Other objects and advantages of the invention will be apparent from the following description and drawing, in which one physical embodiment of my invention is shown, and wherein like numerals refer to similar parts throughout the several views.

In the drawing,
15 Figure 1 is a view in elevation of a section of a cutter bar, a portion of the side wall of the bar being broken away to show the position of the cutter chain.

Figure 2 is a transverse sectional view taken 20 on the line 2—2 of Figure 1.

Figure 3 is an end view of one of the bit carrying links used in the chain, and

Figure 4 is an end view of a connecting link.

The cutter bar of the present invention is 25 formed of the usual chain slide plates 10 secured together in spaced relation by a center bar 11 to form a track in which the cutter chain moves. The cutter bar of the present invention distinguishes from the cutter bars now ordinarily used 30 in that angled wearing strips 12 are riveted upon the inner edges of the outer ends of the chain slide plates, one flange 13 of each wearing strip being positioned upon the outer edge of a slide plate while the other flange 14 extends along the 35 inner wall of the slide plate. This arrangement provides grooves 15 along the inner walls of the cutter bar flanges in which elements of the cutter chain may move to prevent the chain from becoming displaced with respect to the cutter 40 bar.

The cutter chain comprises bit carrying links 18 of the block type and having bits 19 secured 45 therein in any suitable manner, adjacent bit carrying links being pivotally connected by pairs of connecting links 20. The links are provided with recesses 21 on each side thereof at their ends, the inner walls of the recesses being concavely arcuate to conform to the arcuate ends of the connecting links as shown in Figure 1. By this arrangement, the side surfaces of both types of links 50 will be substantially flush. The connecting links 20 are provided on their inner faces with apertured lugs 22 adapted to fit into sockets or bores 23 which extend entirely through the bit carrying links at each end thereof. Pins or rivets 55

24 extend through the apertures in the connecting links to secure the connecting links together and to pivotally hold them properly joined to the bit carrying links.

The bit carrying links 18 include flanges 25 which are adapted to bear upon the flanges 13 of the wearing strips 12 and flanges 26 are provided at the inner ends of the bit carrying links, which flanges move in the grooves 15 of the cutter bar and thereby serve as gibs.

The connecting links 20 are provided with flanges 27 adapted to bear on the flanges 13 of the wearing strips and also include flanges or gibs 28 at their inner ends which move in the grooves 15 of the cutter bar.

As is best shown in Figure 1, the flanges 25 of the bit carrying links may be of a length substantially corresponding to the distance between the centers of the pins 23 and the same is true of the gibs 28 on the connecting links 20. The 20 end surfaces of the gibs 28 may be downwardly inclined, as shown. The wearing strip engaging flanges 27 on the connecting links and the gibs 26 of the bit carrying links are of less length than the distance between the centers of the pins 23. 25 It will be noted that the wear strip engaging flanges 25 and 27 are of maximum length so that a large wearing surface is provided, thereby insuring that the pressure transmitted to the wearing strips will be widely distributed and tilting of 30 the links such as occurs when a bit encounters a hard body of coal in the seam will be resisted.

In the construction provided by the invention of the present application, the wearing strips 12 will be exposed to all of the wear to which the 35 cutter bar would otherwise be subjected, because, as shown in Figure 2, even when the flanges 25 and 27 of the respective links are in contact with the wearing strips, the inner surfaces of the links will not bear upon the center bar 11. Also, the 40 provision of flanges 25 and 27 adapted to bear upon the wearing strips at the ends of the slide plates 10 will provide bearing surfaces relatively close to the cutter bits 19, further reducing the possibility of tilting action of the links. The holding of the links against tilting will permit the 45 entire structure to be used over a longer period of time than is the case where no such flanges are provided.

Tendency of the chain to turn on its longitudinal axis when fed in its own plane with the cutter bit projecting laterally will be resisted by reason of the fact that the side surfaces of the bit carrying links 18 are flush with the side surfaces of the connecting links 20. It can be readily seen 55

- that the side surfaces of the links 18 cooperate with the side surfaces of the links 20 in sliding engagement with the inner walls of the cutter bar flanges to resist tilting. This resistance is 5 supplemented by the resistance against tilting afforded by the gibs 25 and 26 of the respective links. The manner of connecting the links 18 and 20, shown in Figures 2 and 4, also stiffens the chain and thereby further resists tilting.
- 10 It will be obvious that the wearing strips 12 may be readily removed and replaced. Heretofore, when the links have been constructed to bear directly upon the usual center bar and side plate structure, it has been necessary to substantially 15 rebuild the cutter bar in order to correct for wear. It will be understood that the invention is not limited to the details of construction shown in the drawing and described in the specification and that the example of the use of the invention which 20 has been given does not include all of the uses of which it is capable; also, that the phraseology employed in the specification is for the purpose of description and not of limitation.
- I claim:
- 25 1. In combination, a link cutter chain comprising alternate bit carrying and connecting links and a cutter bar including spaced flanges between which the chain moves, said flanges being longitudinally grooved at their inner ends, each 30 link of said chain being provided with flanges to bear upon the outer edges of the cutter bar flanges and gibs to engage the grooves in the cutter bar flanges.
2. In combination, a link cutter chain and a cutter bar including spaced outwardly projecting flanges between which the chain moves, each link of said chain being provided with flanges to bear upon the outer edges of the cutter bar flanges to 35 distribute the pressure of the chain over a maximum area of the cutter bar flanges.
3. In combination, a link cutter chain and a cutter bar including spaced flanges, wear strips secured to the free ends of the cutter bar flanges, each link of said chain being provided with 40 flanges to bear upon the outer edges of the wear strips to distribute the pressure of the chain over a maximum area of the wear strips.
4. In combination, a cutter chain and cutter bar, the cutter bar being provided with an undercut 45 groove in which the chain moves, the chain comprising bit carrying links and interspersed connecting links, each of said types of links including a body portion moving in the cutter bar groove, a flange bearing upon the edges of the bar, and gibs moving in the undercut portion of the bar, the bit carrying links including a bit holding block projecting past said flanges.
5. In combination, a cutter chain and cutter bar, the cutter bar being provided with an undercut 50 groove in which the chain moves, the chain comprising bit carrying links and interspersed connecting links, each link of the chain being provided with flanges to bear upon the outer edges of the cutter bar flanges to distribute the pressure of the chain over a maximum area of the cutter bar flanges, the flanges of the bit carrying links each having a length approximately equal to the distance between the pivots of the bit carrying links.

connecting links, each of said types of links including a body portion moving in the cutter bar groove, a flange bearing upon the edges of the bar, and gibs moving in the undercut portion of the bar, the bit carrying links including a bit holding block projecting past said flanges, pin members connecting said links, the gibs of one of said types of links and the flanges of said other type of link extending longitudinally a distance corresponding to the distance between the axes of 10 said pins.

6. In combination, a link cutter chain comprising alternate bit carrying and connecting links and a cutter bar including spaced flanges and wear strips secured to the free ends of the cutter 15 bar flanges, the chain being arranged to move between and upon the wear strips, each link of the chain being provided with flanges to bear upon the outer edges of the wear strips and gibs to engage the inner edges of the wear strips. 20

7. In combination, a cutter chain and cutter bar, the cutter bar being provided with a groove in which the chain moves, the chain comprising bit carrying links and interspersed connecting links, each type of said links including a body 25 portion moving in the cutter bar groove, and a flange bearing upon the edges of the bar, the bit carrying links each including a bit holding block projecting past said flanges.

8. In combination, a link cutter chain including bit carrying links and connecting links having their outer surface flush with each other on opposite sides of the chain and a cutter bar including spaced outwardly projecting flanges between which the chain moves, L-shaped wear 35 strips secured to the inner walls and outer edges of said flanges to provide inner laterally extending grooves, the bit carrying links of the chain being provided with outwardly projecting flanges bearing upon the wear strips on the outer edges 40 of the cutter bar flanges and with gibs movable along said grooves, tilting of the chain on an axis parallel to the path of movement of the links during feed of the chain cutter being resisted not only by the gibs fitting the wear strips and the 45 grooves but also by said flush surfaces of both the bit carrying links and connecting links fitting the inner opposite walls formed by the wear strips between the cutter bar flanges.

9. In combination, a link cutter chain and a cutter bar including spaced flanges between which the chain is adapted to move, said chain comprising bit carrying links and connecting links and each link of the chain being provided with flanges to bear upon the outer edges of the cutter bar flanges to distribute the pressure of the chain over a maximum area of the cutter bar flanges, the flanges of the bit carrying links each having a length approximately equal to the distance between the pivots of the bit carrying links. 80
